(57) **CLAIM**

The ornamental design for a track for a shelving system, as shown and described.

DESCRIPTION

FIG. 1 is a front perspective view of a track for a shelving system, showing my new design;

FIG. 2 is a back perspective view of the track for a shelving system shown in FIG. 1;

FIG. 3 is a left side elevation view of the track for a shelving system shown in FIG. 1;

FIG. 4 is a right side elevation view of the track for a shelving system shown in FIG. 1;

FIG. 5 is a front elevation view of the track for a shelving system shown in FIG. 1;

FIG. 6 is a back elevation view of the track for a shelving system shown in FIG. 1;

FIG. 7 is a bottom plan view of the track for a shelving system shown in FIG. 1;

FIG. 8 is a top plan view of the track for a shelving system shown in FIG. 1; and,

FIG. 9 is a perspective view of the track for a shelving system shown in FIG. 1 being used to support a standard. The broken lines are shown for illustrative purposes only and forms no part of the claimed design.
